Fig. 8.

A technical drawing of a mechanical component. It features a horizontal rectangular beam with a central slot. On the left side, there is a vertical support structure with a central slot. Two circular features, labeled 17, are attached to the vertical support structure. Two other circular features, labeled 18, are attached to the horizontal beam. Two small circular features, labeled 19, are positioned above the horizontal beam. The entire assembly is mounted on a base, with a label 10 at the top center.

UNITED STATES PATENT OFFICE.

CHARLES B. OSBON, OF SOMERVILLE, MASSACHUSETTS.

SHIP'S DAVIT.

1,401,919.

Specification of Letters Patent. Patented Dec. 27, 1921.

Application filed May 26, 1920. Serial No. 384,409.

To all whom it may concern:

Be it known that CHARLES B. OSBON, a citizen of the United States, and resident of Somerville, county of Middlesex, and 5 Commonwealth of Massachusetts, has invented an Improvement in Ships' Davits, of which the following description, in connection with the accompanying drawings, is a specification, like characters on the 10 drawings representing like parts.

This invention relates to ship's davits and its object is to provide an improved construction that will permit safe and expeditious launching of a boat on an even keel from 15 a vessel in any kind of a sea, and likewise the hoisting of a boat to the deck of a vessel.

In the drawings of one embodiment of my invention illustrated and described herein:

20 Figure 1 is a plan, showing the boat swung outboard from the vessel's side and ready to be lowered into the water or swung inward and lowered on the chocks;

Fig. 2, a side elevation showing the boat 25 just raised from its chocks.

Fig. 3, an end elevation on an enlarged scale;

Fig. 4, a detail plan on an enlarged scale 30 of the boat hoisting and lowering winches and their operating gears, and the davits' swinging winches and their operating gears;

Fig. 5, an enlarged detail side elevation of the raising and lowering winches;

Fig. 6 an enlarged side elevation detail 35 on the line 6-6 Fig. 4, looking in the direction of the arrow;

Fig. 7, a similar view on the line 7-7, Fig. 4;

Fig. 8, an enlarged side view detail of 40 the falls on the, Fig. 1, left hand end of the davits;

Fig. 9, a detail plan enlarged of the Fig. 2 left hand end of the davit base and boom, the cross beam broken away; and

45 Fig. 10, a side elevation of the same end from the left, Fig. 1.

Referring first to Figs. 1, 2, my novel construction comprises bases 1, 2, each having side members 3, 4, spaced apart and secured by flanges 5 to the deck 6, the bases being a suitable distance apart as desired, to accommodate the size of the boat used.

To avoid the inconvenience and danger which have always accompanied the use of 50 the horizontally swinging davits, I have conceived the novel plan of using Figs. 1,

2, vertically swinging davits 8 mounted on horizontal pivot bearings 9 in the bases 1, 2.

The davits are connected by a cross-bar 10. The swinging action of the davits 8, 60 Figs. 1, 2, 3, is immediately controlled, and their positions both inboard or normal, and when outboard or in use, determined by booms 11, pivoted to the davits near their upper ends and carrying, each at its lower 65 end, a pin or roll 12 adapted to slide in slots 13 in the opposite side members 3, 4, of the base.

The rolls 12 rest against the upper end of the slots when the davits are swung out for 70 use, see dotted lines Fig. 3, and, same figure against the opposite ends of the slots normally or when the davits are not in use.

I will now proceed to describe the davit operating means for launching the boat, 75 which normally rests upon the chocks 14 on deck. Secured to the bow 15 of the boat Figs. 2, 4, 5, is a cable 17 which passes through a block 18, over a fixed pulley 19 on the cross-bar 10, down beneath a pulley 80 20 slidable on a bar 21 in the standard 22, base 2, and standard 23, on the deck 6, to permit even winding of the cable thereon, the cable running therefrom about a winch 24 to which it is secured. While the standards 22, 23, are here shown as single flat sheets of sheet steel, obviously they may be 85 of any desired suitable configuration.

From the stern of the boat, Figs. 2, 4, 5, a cable 26 runs through a block 27 suspended 90 likewise from the cross-bar 10, thence lengthwise thereof over the fixed pulley 19 and through the swinging block 28 down beneath a similar pulley 29 on the bar 21 up and about the winch 30, with the winch 24, 95 on a common shaft 31 in the standards 22, 23.

On the winch 30, Figs. 4, 5, are the gear wheels 32 and 33. The former is adapted to and is shown as in mesh with a pinion 34 on a shaft 35 mounted in the standards 22, 100 23, and extended through the walls 3, 4, of the base 2, and the gear 33 has a pawl 36 on the standard 23 to act thereon. On the winch 30 is a drum 38 about which extends a brake band 39, one end of the same, Figs. 105 5, 6, being secured to a pin 40 extended laterally from the standard 23, while its opposite end is pivoted to an arm 41 on the bar 21. On the Fig. 5 right hand end of the bar 21 is a brake lever 42 also see Fig. 3, 110 for operating this brake band with a pawl or dog 43 on its upper end adapted to en-

gage slots 44 in a plate or bar 45 on the standard, the dog being operated by a handle 46. By rotation of the shaft 35 and winches 24, 30, through the cranks 37 obviously the cables 17, 26, will be wound thereon or unwound therefrom, and the boat raised or lowered.

For swinging the davits out from the deck preparatory to raising or lowering the boat 10 I have invented the following novel means.

Besides the winches 24 and 30, Fig. 4, are the two smaller davit swinging winches 48, 49, also on a common shaft 50 mounted in the standards 22, 23. On the shaft is a gear 15 51 also adapted to mesh with the pinion 34 on the shaft 35 which is slidable longitudinally for this purpose.

To lock the pinion 34 in engagement with either gear 32 or 51, Fig. 4, the shaft 35 20 carries a flanged collar 52 fast thereon. When the gears 34, 32 are engaged, they may be locked by dropping the pawl 53, Fig. 4, pivoted to the standard 23, down upon the shaft between the flanged collar and stand- 25 ard 23.

When the gears 34, 51 are engaged they may be so locked by dropping the pawl 53 down upon the collar 52, a cut away portion 30 54, of the pawl, Fig. 6, fitting over the flange on the collar and preventing it and the shaft 35 from moving longitudinally.

On the outer end, Fig. 4, lower end of the shaft 50 is a ratchet wheel 55 and a pawl 56 on the standard 23 engages the same. On 35 this shaft also, Fig. 3, beside the ratchet, is a drum 57, about which is a brake band 58, one end of which is secured to a pin 59 in the standard 23, while the opposite end is pivoted to a foot brake lever 60, Fig. 6, 40 pivoted also to the standard 23.

To the winch 48, Figs. 1, 4, is fastened a cable 62 which runs through a block 63 on the base and then to and over a pulley 64 at the bottom and on the inner side of the 45 wall 4 of base 1 thence forward between the walls 3, 4, and, Fig. 19, around a pulley 65 mounted in the members 3, 4, right hand end Fig. 2 and thence rearwardly to the lower end of the boom 11. A turnbuckle 68 50 may be introduced into the cable 62 if desired for adjustment of the same to meet necessary requirements.

From the winch 49, Fig. 4, runs a cable 70 fast thereon over a pulley 71 on the Fig. 55 1 left hand wall of the base 2, and from thence it runs Fig. 7, forwardly between the walls 3, 4, over a pulley 72 and then to the lower end of the boom 11.

It will be clear that by winding up the 60 cables 62, 70, upon the winches 48, 49, the cables will draw the lower ends of the booms 11 outwardly, and upwardly, Figs. 3, 7, to the left, the rolls 12 sliding in the slots 13 in the side members 3, 4.

65 On one side wall, herein 3, Figs. 4, 9, in

each case, is a ratchet bar 73 to be engaged by a pawl 74 on the end of the boom 11 and like it when it is in raised or outward position, so that rolling of the vessel may not act to cause the boom to slide inwardly and downwardly and get out of control of the operator.

In each base Fig. 7, and just below the slot 13 is a stop in the form of an adjustable pulley 75 in a block 76 slidable in a slot 77 in each side member 3, 4, movement of the block and pulley being controlled by a wheel 78 on a shaft 79 threaded into the upper, Fig. 7, left hand end of the block, the wheel being positioned in a slot 80 in the wall member 80 and thus kept from traveling.

Obviously the positions of the pulleys 75 in the slots 77 will determine the extent to which the booms 11 can be moved upward in the slots 13 before the chains 70, 62 contact therewith, and normally the pulleys 75 are so positioned that they will permit the booms 11 to be raised by the cables 62, 70, sufficiently to swing the davits 8 outward just beyond the perpendicular. Then when 90 the davits are in outermost position the boat will drop by gravity clear of the ship's deck when the cables 17, 26 are released from the winches 24, 30, by the brake 42. If however, the sea is rough and the ship rolling badly 95 and there is necessity for more leeway to prevent the boat from striking the vessel when the boat is lowered, the wheels 78 are turned and the blocks 76, and pulleys 75 raised to permit the boom ends to be raised higher 100 and thus swing the davits farther out and away from the ship.

The method of using my invention is as follows:

The boat Fig. 2, normally rests upon the 105 chocks 14 with the cables 17, 26, secured thereto and running through the blocks or falls as described.

The davits 8 and booms 11 will occupy the positions shown in Figs. 2, 3, 7, the 110 pawls 74, Figs. 1, 9, lowered to engage the ratchet bars 73.

The shaft 35 is first withdrawn, Fig. 4, i. e., toward the bottom of the figure, so that the pinion 34 will engage the davit swinging winch gear 51 and locked in that position by dropping the pawl 53 in position to engage the collar 52. Pawl 56 will 115 6 also be in engagement with gear 55 to lock the winches securely against backward motion as the cables are wound upon them.

One or both cranks 37 as may be necessary are turned to the right Fig. 4, to wind the cables up on the winches 48, 49, and thus move the davits 8 and booms 11, to the 125 left until the lower ends of the booms are nearly vertically over the pulleys 75 over which the cables 62, 70 run, which is usually as far as the boom ends need be raised. At this point the cables 62, 70, Fig. 7, each 130

engages a pulley 75 and prevents further raising of the booms which during the previous movement have raised the boat from its chocks. The davits 8 will now be positioned outboard, dotted lines, Fig. 3, just beyond the perpendicular. From this point, the pawl 56 being now raised to permit unwinding of the cables 62, 70, the weight of the boat will swing davits to their outermost position, see Fig. 7, dotted lines and Fig. 1, their swinging movement being controlled as to speed by the foot brake 60, either with or without the use of the cranks 37, the cables 62, 70, unwinding in the meantime until the rolls 12 engage the upper ends of the slots 13, Fig. 3.

As already stated, the lateral position of the roll 75 relative to the pulley 72 may be adjusted at will to suit any particular case by turning the wheel 78 which moves the block 76 and the roll 75 up or down in slot 77, and thus determines how far the lower ends of the booms 11 may be raised by the cables 70, 62, attached thereto and running over the pulleys 72 and of course how far outboard the upper ends of the davits 8 may extend.

After raising the pawl 36 to free the ratchet 33 and winches 24, 30, the boat may be lowered to a level with the deck 6 to receive passengers if desired, and next lowered into the water and by means of the hand brake 42 these winches are controlled and permitted to rotate in the rearward or Fig. 4, left hand direction slowly unwinding the cables 17, 26, and allowing the boat to descend gradually into the water.

To raise the boat from the water the pawl 36 is dropped into engagement with the gear 33, shaft 35 is slid inwardly until pinion 34 meshes with gear 32 and locked there by the pawl 56. Then by turning the cranks 37 to the right, Fig. 4, the cables 17, 26, are wound upon the winches 24, 30, until the boat is raised to the proper height.

Then the shaft 35 is again slid longitudinally outward, Fig. 4 downward, until pinion 34 meshes with gear 51. The cranks 37 are turned to the left, Fig. 4, winding up cables 62, 70, on the winches 48, 49, and swinging the davits 8 and booms 11 inboard until each roll 12 is positioned substantially over a pulley 75 when the pawl 56 is raised to free the ratchet 55 and permit unwinding of the cables 62, 70, and the davits and boat are swung inboard by the sailors, the movement of the booms being controlled by the foot brake 60.

Thereafter the boat may be lowered into the chocks by the winches 24, 30, or by a little experience the boat may be raised from the water to such a height that when the davits are swung inboard the boat will slide naturally into the chocks.

By my improved construction the boat

may always be swung outboard on an even keel under such control that the men at either davit in control of the cables, are not in danger of precipitating one end of the boat into the water ahead of the other end.

Both ends of the boat will drop simultaneously and will rise simultaneously, and both ends are swung outboard and inboard at the same time.

My invention is not limited in all its details to the precise embodiment illustrated herein, and its scope will be indicated by the claims.

Claims—

1. Boat launching apparatus comprising a base, a davit movable thereon, davit controlling means including a boom and a winch therefor, locking means on the base for locking the boom against backward travel, a movable stop on the base for determining the extent of outward travel of the boom, boat lowering means including a winch, and common operating means for the winches.

2. Boat launching apparatus comprising a base, a davit movable thereon, davit controlling means including a boom slideable on the base and normally at rest at the inner end of said base, a winch for moving said boom, a movable stop for the boom, boat lowering means including a winch, and common operative means located with said winches between the boom and davit on the base.

3. Boat launching apparatus comprising a base, a davit movable thereon, davit controlling means including a boom slideable angularly upward on the base, a winch therefor beneath the path of travel of the lower boom end, boat lowering means including a winch, and common operative means longitudinally adjustable to operate both winches.

4. Boat launching apparatus comprising a base, a davit movable thereon, a boom connected with the davit and having one end slideable in said base, a stop member for the boom below the path of travel of the lower boom end to determine adjustably the distance of travel of the boom, a winch for moving the boom and mounted in the base, a winch for moving the davit, gears on the winches, an operating shaft on the base having a pinion, said shaft movable in its bearings to cause it to engage either winch gear, and brakes for the winches.

5. Ship's davits comprising vertically swinging davit members, bases therefor, booms for the davits having slideable connections with the bases, a pin on each boom end seated in a slot, an adjustable pulley on the base, and a cable thereon connected with the boom end to swing the davits outboard and inboard.

6. Ship's davits comprising vertically

- swinging davit members, bases therefor, booms for the davits having slideable connections with the bases, comprising a slot in each base, a pin in each boom and seated in said slot, an adjustable pulley on the base, a cable thereon connected with the boom end, and a winch for winding the cable to swing the davits outboard and inboard.
- 10 7. Ship's davits comprising vertically swinging davit members, a winch for hoisting a boat thereon, bases for the davits, booms for the davits having slideable connections with the bases comprising a slot in each base, a pin in each boom and seated in said slot, an adjustable pulley on the base, a cable thereon connected with the boom end, and a winch for winding the cable to swing the davits outboard and inboard.
- 15 8. Boat launching apparatus comprising a plurality of bases, a davit and boom movable on each base, stop members therefor adjustable on the bases to determine the length of travel of the booms and davits, and a winch on one base for moving the booms, a winch for moving the davits, gears on the winches, an operating shaft on one base having a pinion, said shaft being movable on the base to cause it to engage either winch gear, and brakes for the winches.
- 20 9. Boat launching apparatus for launching and raising a boat on an even keel comprising bases, davits movable thereon, booms for the davits connected therewith and also movable on the bases, adjustable stops on the bases to determine the extent of travel of the booms, a boom winch, cables for moving the booms by the winch to swing the davits outward and raise the boat on an even keel from the chocks, a boat winch, and cables thereon for lowering the boat on an even keel.
- 25 10. Boat launching apparatus comprising bases, vertically swinging davits thereon, controlling means therefor including booms having sliding connection with the bases and a winch, boat lowering means including a second winch and means including a movable shaft for simultaneously throwing the boom operating winch out of and the boat lowering winch into operation.
- 30 11. Boat launching apparatus comprising bases 1, 2 with slots 13 therein, vertically swinging davits 8 mounted on the bases and connected together, booms 11 pivoted to the davits, with pins 12 at their inner ends and adapted to slide in the slots 13, a ratchet bar 73 on each base, a pawl 74 on each boom to engage the same, a slot 77 in each base with a block 76 and pulley 75 thereon slideable therein, a shaft 79 with wheel 78 threaded to said block, slots in the bases 1, 2 with the wheels 78 positioned therein; the bar 21 in the base with pulleys 20, 29; winches 24, 30 on the shaft 31 in the standards 22, 23 on the base 1, gears 32, 33 on the winch 30, davit winches 48, 49 on the shaft 50 in said standards 22, 23, gear 51 on the winch 49, a shaft 35 with crank 37 in the base 1 with pinion 34 thereon adapted to mesh with either gears 51 or 32; a flange collar 52 on the shaft 35 and pawl 53 adapted to rest thereon to hold the gear 34 in mesh with either gear 32 or 51, falls for connecting the boat with two of said winches and falls for connecting the booms with two of said winches whereby the davits may be raised to a substantially vertical position raising the boat from the chocks, and the boat may be lowered on an even keel to the water, and brakes for controlling the action of the winches.
- 35 In testimony whereof I have signed my name to this specification.
